Primary Examiner — W. A. Teddy Falloway*Assistant Examiner* — Amanda Kay Birdwell(57) **CLAIM**

The ornamental design for a spout for a beverage can, as shown and described.

DESCRIPTION

FIG. 1 is a front perspective view of a spout for a beverage can in accordance with the subject disclosure.

FIG. 2 is a rear perspective view thereof;

FIG. 3 is a bottom perspective view thereof;

FIG. 4 is a front perspective view thereof;

FIG. 5 is a rear perspective view thereof;

FIG. 6 is a front view thereof;

FIG. 7 is a cross-section view taken along and in the direction of line 7-7 in FIG. 6 thereof;

FIG. 8 is a rear view thereof;

FIG. 9 right-side view, the left side being a mirror image thereof;

FIG. 10 is a top view thereof; and,

FIG. 11 is bottom view thereof.

The broken lines shown illustrate environmental structure and form no part of the claimed design.

1 Claim, 9 Drawing Sheets(56)
